Clifford V. King, 14 Lennon Place, Whitesboro, N.Y.

Filed Mar. 18, 1964, Ser. No. 79,069

Term of patent 14 years

(Cl. D41—1)

FIG. 1

FIG. 2

FIG. 3

FIG. 4

FIG. 1 is a perspective view of a wheel chock embodying my new design.

FIG. 2 is a side elevation of the same at slightly reduced scale.

FIG. 3 is a side elevation of the same as seen from the left of FIG. 2.

FIG. 4 is a plan view of the same as seen from above FIG. 2.

The side opposite FIG. 2 is a mirror image of FIG. 2. The cleats on the bottom shown in FIGS. 1 and 2 extend clear across the bottom, which is otherwise flat and plain.

I claim:

The ornamental design for an automobile wheel chock, as shown and described.
